DESIGN FOR A DRESS ENSEMBLE

Max Reich, Chicago, Ill.

Application August 24, 1938, Serial No. 79,531

Term of patent 3½ years

To all whom it may concern:

Be it known that I, Max Reich, a citizen of the United States of America, residing in Chicago, county of Cook, and State of Illinois, have invented a new, original, and ornamental Design for a Dress Ensemble, of which the following is a specification, reference being had to the accompanying drawing, forming part thereof, wherein,

The characteristic feature of my design resides in the combination on the ensemble disclosed of the specific arrangement of large and small nail-heads on the particular jacket and on the sleeves of the specific dress as shown.

I claim:

The ornamental design for a dress ensemble, substantially as shown and described.

MAX REICH.
